Des. 241,755
Patented Oct. 5, 1976

241,755

SANITARY CAT PAN

Henry E. Lowe, Jr., Cassopolis, Mich.
(Jones, Mich. 49061)

Filed Apr. 23, 1975, Ser. No. 570,658

Term of patent 14 years

Int. Cl. D30—99

U.S. Cl. D30—99

Fig. 1

Fig. 2

Fig. 3

Fig. 4

Fig. 5

FIG. 1 is a perspective view of a sanitary cat pan showing my new design;

FIG. 2 is an exploded rear perspective view thereof;

FIG. 3 is a cross-sectional view taken along line 3—3 of FIG. 1;

FIG. 4 is a top plan view; and

FIG. 5 is a cross-sectional view taken along line 5—5 of FIG. 4.

I claim:

The ornamental design for a sanitary cat pan, substantially as shown and described.
